UNITED STATES PATENT OFFICE

140,476

DESIGN FOR A BOTTLE CARRIER

Frederick E. Green, Toppenish, Wash.

Application April 18, 1944, Serial No. 113,300

Term of patent 14 years

(Cl. D58—4)

To all whom it may concern:

Be it known that I, Frederick E. Green, a citizen of the United States, residing at Toppenish, in the county of Yakima and State of Washington, have invented a new, original, and ornamental Design for a Bottle Carrier, of which the following is a specification, reference being had to the accompanying drawing, forming part thereof.

The drawing is a perspective view of a bottle

carrier, showing my new design, the end panel opposite to the end panel shown, containing a substantially like surface ornamentation as that on the outer panel surface shown.

I claim:

The ornamental design for a bottle carrier, as shown and described.

FREDERICK E. GREEN,
